UNITED STATES PATENT OFFICE.

HENRY SCHLUTZ, OF PITTSBURGH, PENNSYLVANIA.

SOCKET WRENCH.

Application filed January 30, 1922. Serial No. 532,542.

To all whom it may concern:

Be it known that I, HENRY SCHLUTZ, a citizen of the United States, residing at Pittsburgh, in the county of Allegheny and 5 State of Pennsylvania, have invented certain new and useful Improvements in Socket Wrenches, of which the following is a specification.

This invention relates to improvements in 10 socket wrenches more particularly upon the construction of wrench disclosed in Letters Patent No. 1,395,656, granted me Nov. 1, 1921, and besides embodying the objects and advantages set forth in connection with the 15 said Letters Patent, the invention has for its further object to provide a wrench of such type having a pair of sliding jaws each formed with a shank, and further embodying means to relieve the torsional or lateral 20 strains or stresses on the jaw-shanks, when the jaws are shifted from normal.

A further object of the invention is to provide a wrench of such class, in a manner as hereinafter set forth, with means whereby 25 by the sliding jaws can be shifted by a pair of operating screws actuated by the thumb and one finger of an operator in the same directions.

A further object of the invention is to 30 provide a wrench of such class, with means, in a manner as hereinafter set forth, with an abutment element constituting means to prevent lateral or torsional strains or stresses with respect to the jaw-shanks, and 35 to further constitute a combined jaw-shank support and guide.

Further objects of the invention are to 40 provide a socket wrench which is simple in its construction and arrangement, very compact when closed, adjustable to fit bodies of various sizes, strong, durable, efficient in its use, conveniently operated, and comparatively inexpensive to manufacture.

With the foregoing and other objects in 45 view, the invention consists of the novel construction, combination and arrangement of parts hereinafter set forth, and illustrated in the accompanying drawing, wherein is shown an embodiment of the invention, 50 but it is to be understood that changes, variations, and modifications can be resorted to which come within the scope of the claim hereunto appended.

In the drawing forming a portion of this 55 specification and wherein like numerals of

reference designate corresponding parts throughout the several views:—

Figure 1 is a vertical sectional view of the body portion of the wrench having one of the jaws mounted therein. 60

Fig. 2 is a similar view taken at right angles thereto and with both jaws mounted thereon.

Fig. 3 is a vertical elevation of a socket wrench in accordance with our invention. 65

Fig. 4 is a perspective view of the jaws.

Fig. 5 is a top plan view of the device with the jaws thereof in the distended position.

Referring in detail to the drawing 1 denotes the stock or body portion of the wrench, provided at its lower end with a polygonal shank 2, having a transversely disposed aperture 3. The shank 2 is adapted for the reception of a socketed handle for 70 operating the wrench, and the aperture 3 for the reception of an operating bar for the same purpose if location of the work permits of its use.

At its upper end, the body portion is 80 formed with a pair of spaced jaw guiding members 4, 4', connected by an integral yoke 5, which with said guiding members 4, 4' provide a housing for the shanks 6 of the jaws, to be described, thus effectually 85 securing said jaws against vertical and lateral movement relative to the said guiding members.

Each of the shanks 6 carries a vertically disposed jaw 7. The two jaws are of a 90 form suitable to grasp the head of a polygonal nut or bolt or other object which is to be operated. The working faces of the jaws 7 are preferably engrafted, as indicated at 8, to augment their gripping action. 95

The two jaws and jaw supporting shanks are counterparts in all respects. In the case of each jaw, there is provided an integral spacing portion 9 which elevate respective jaws so that their lower edges are flush with 100 or very slightly above the surface of the yoke 5, said spacing portions 9 approximating the thickness of said yoke.

Referring to each of the jaws 7, it will be observed that the spacing portion 9 thereof, is provided with a shoulder 10, which cooperates for interlocking engagement with a corresponding recessed portion 11 on the end of the shank 6, of each of the jaws 7, to limit movement of the jaws 110

toward each other. During adjustment operations of the jaws the inner faces of the two shanks 6 bear against each other as is clearly seen in Figure 2, the cross-sectional area of the two approximating that of the space between the guiding members 4, 4'.

A longitudinally extending abutment member 12 is formed integral with the upper face of the body portion 1, intermediate of the jaw guide members 4, 4'. The lower inner face of each of the shanks 6 is formed with a recess 13 in engagement with the abutment member 12.

As clearly illustrated in Figure 2 and 3, the width of the recesses 13 of the two shanks 6 combined is commensurate to the width of the abutment member 12, against which they operate.

The engagement of the shanks 6 with the abutment member 12 serves to counteract and carry the lateral strain or twist to which said shanks are necessarily subjected when in the distended position.

Upon the lower outer faces, the shanks 6 are provided with a series of rack teeth 14 for the purpose to be described. Extending transversely through the body portion 1 of the wrench, and at right angles to that formed by the grinding members 4, 4', is an opening 26 adapted to receive rotary operating screws 15 journaled in bearings 16 in the body portion 1.

The screws 15 are knurled to facilitate rotation, for instance by the thumb and index

finger, and extend slightly beyond the opening 26 upon each side of the body portion respectively, and mesh with the rack teeth 14 upon the jaw shanks 6.

The construction of the jaws and shanks being identical and mounted between the jaw guide members 4, 4', from respective sides of the body portion 1, it will be seen that the rotation of the screws 15 in the same direction will cause a simultaneous movement of the jaw elements in opposite directions, the contraction or distention of the two jaws, relative to each other, being determined by the direction of rotation of the screws.

What I claim is:—

A socket wrench comprising a stock having a recessed portion, oppositely disposed jaws provided with shanks slidably mounted in said recess, each of said shanks having a bevelled outer portion formed with rack teeth, the teeth on one shank being oppositely disposed with respect to the teeth on the other shank, operating screws journaled in said stock and meshing with said racks for shifting the jaws, the threads of said screws being oppositely disposed relatively to each other, an abutment positioned at the bottom of said recess, and said shanks having their lower ends opposing and overlapping said abutments.

In testimony whereof I affix my signature.

HENRY SCHLUTZ.
